UNITED STATES PATENT OFFICE.

CHARLES W. STARKER, OF PITTSBURGH, PENNSYLVANIA, ASSIGNOR TO WESTINGHOUSE ELECTRIC AND MANUFACTURING COMPANY, A CORPORATION OF PENNSYLVANIA.

FRAME STRUCTURE FOR DYNAMO-ELECTRIC MACHINES.

1,314,545.

Specification of Letters Patent.

Patented Sept. 2, 1919.

Application filed October 21, 1916. Serial No. 126,910.

To all whom it may concern:

Be it known that I, CHARLES W. STARKER, a subject of the Emperor of Germany, and a resident of Pittsburgh, in the county of 5 Allegheny and State of Pennsylvania, have invented a new and useful Improvement in Frame Structures for Dynamo-Electric Machines, of which the following is a specification.

10 My invention relates to dynamo-electric machines and especially to certain structural features of frames for electric-railway motors and the like.

One object of my invention is to provide 15 a structure of the above-indicated character which shall be capable of ready modification to provide a series of motor frames of the same dimensions and capacity, with the exception of the "gear-center-distance," that 20 is, the distance between the center of the armature shaft and the center of the truck axle.

Another object of my invention is to provide 25 a structure of the class in question which shall also be readily adaptable to produce different "road clearances," that is, the distance between the road bed and the bottom of the motor frame, for any given height of car-floor above the rails.

30 More specifically stated, the object of my invention is to provide a main yoke member for dynamo-electric machines having a gap in one side, the edges thereof being offset a selected amount and angle to provide any 35 desired "gear-center-distance" and "road clearance," as more fully set forth later.

My invention may best be understood by 40 reference to the accompanying drawings, wherein Figure 1 is a view, chiefly in end elevation but partially in section, of a dynamo-electric machine frame constructed in accordance with my present invention; Fig. 2 is a view taken on the line II-II of Fig. 1 and illustrating the interior construction of a portion of the motor frame that is 45 shown in Fig. 1; and Fig. 3 is a view corresponding to the sectioned portion of Fig. 1 and showing a modification whereby a different "gear-center-distance" and "road 50 clearance" are secured.

Referring to Fig. 1 and Fig. 2 of the drawings, the structure shown comprises a

main yoke or band member 1, preferably of the customary polygonal shape and having a gap or opening 2 in one side thereof, the 55 edges 3 and 4 of which are offset a selected amount from the adjacent portions of the machine frame, for a purpose to be described; an axle-bracket 5 that is adapted to bridge the gap 2 and is mechanically secured to 60 the offset portions 3 and 4, as hereinafter set forth in detail; a plurality of end-members or end-rings 6 that are associated with the respective ends of the main yoke member 1; a plurality of connecting members or 65 tie-pieces 7; and a suspension bar 8.

In a co-pending application of M. B. Lambert and C. W. Starker, Serial No. 121,417, filed Sept. 21, 1917, and assigned to the Westinghouse Electric & Manufacturing 70 Company, is set forth and claimed a dynamo-electric machine frame member corresponding to the present member 1 and having a gap in one side, the edges of which are not offset, but are located in alinement 75 with the adjacent inclined portions of the frame. In order to adapt such a construction to the production of a complete line of motor frames having various "gear-center-distances," the necessity for which variation 80 is well-known to those skilled in the art and need not be discussed here, I have found that, by offsetting the edges of the side gap in the manner illustrated in Fig. 1, any desired "gear-center-distance" may be secured 85 without requiring much additional material, time or labor and without, in any way, impairing the desirable mechanical and electrical characteristics of the machine.

As will be understood, the degree of offset 90 of the portions 3 and 4 will determine the initial length of the flat slab from which the main yoke member 1 is made and the substantially regular polygonal frame that is set forth in the above-identified co-pending 95 application may then be formed by the use of the same set of dies that is employed for other lengths of slab. By subsequently offsetting the edges 3 and 4 of the frame member, which requires only a simple mechanical 100 process, the desired variation of "gear-center-distance" may readily be obtained.

The offset portions 3 and 4 are respectively provided with suitable holes or openings 9

and 10, whereby the axle-bracket 5 may be readily riveted thereto, as subsequently more fully set forth.

The axle-bracket 5 may be of any suitable form, but is preferably of the pressed-steel type that is disclosed in Patent No. 1,198,080 granted on September 12, 1916, to C. W. Starker and G. L. S. Kronfeld. Consequently, only a brief description of the illustrated axle-bracket, concerning particularly its relation to the offset portions 3 and 4, is believed to be sufficient for the purposes of the present specification.

The axle-bracket shown comprises a substantially semi-cylindrical intermediate portion 11 having lips or wings 12 and 13 respectively bent over the offset portions 3 and 4 of the main yoke member 1 and secured thereto by a plurality of rivets 14 and 15, which extend through the holes 9 and 10 of the offset portions 3 and 4, respectively. The axle-bracket is also provided with relatively flat side members 16 and 17 near the respective ends of the axle-bracket for the purpose of suitably receiving an axle-cap (not shown), in accordance with customary practice.

The end-rings 6 may be of any suitable construction and are here shown as comprising shallow cup-shaped members having a flat outer face that is provided with a central opening 20 for the purpose of receiving a suitable armature bearing-housing (not shown), in accordance with the usual practice. The edges of the opening 20 are preferably reinforced by means of a plate 21 of triangular or other form.

The connecting members or tie-pieces 7 are preferably formed of pressed-steel and are provided with one or more pressed-out ribs or bosses 22 for the purpose of obtaining a maximum of resistance to deformation with a minimum weight of material.

A plurality of rivets 23 extend through convenient flat portions 24 of the tie pieces 7 and also extend through the adjacent portions of the main yoke member 1 or of the end rings 6, as the case may be.

The suspension bar 8 may be of any suitable type for performing the intended function of supporting the motor upon a truck frame (not shown), in accordance with customary practice and is secured to the yoke member 1 and the end rings 6 by a plurality of rivet members 25.

Although a brief description of the frame members 6, 7 and 8 has been given, it is thought that no more extended discussion thereof is necessary, particularly in view of the fact that the specific construction thereof is not material to my present invention and, moreover, the illustrated structures are fully set forth in the above-identified co-pending application.

Fig. 3 discloses a portion of a main yoke

member 21 which corresponds to the previously-described yoke member 1 and is provided with the offset portions 3 and 4 which, however, are offset from the adjacent portions of the frame member 21 a greater amount and a different angle than the portions 3 and 4 are offset from the adjacent portions of the main yoke member 1. Consequently, it will be understood that, in the case of a frame that is constructed in accordance with the dimensions of Fig. 3, the point C2, which represents a point in the center of the truck axle (not shown) is further removed from the point 0 (see Fig. 1), which represents a point in the center of the motor armature shaft (not shown), than is the point C1 of Fig. 1, which corresponds to the point C2, or, in other words, the "gear-center-distance" in the case of Fig. 3 is longer by a predetermined distance, dependent upon the amount of offset of the portions 3 and 4, than the "gear-center-distance" of the structure that is shown in Fig. 1. Furthermore, the angle that the offset portions 3 and 4 make with the adjacent main inclined portions of the frame member 21 is less than the angle that the corresponding parts make with each other in the structure that is illustrated in Fig. 1, by reason of the upward tilting of the portions 3 and 4 in the structure of Fig. 3. Consequently, the point C2 is located in a higher horizontal plane than the point C1. By tilting the offset portions 3 and 4 downwardly, the point C2 will be located in a lower horizontal plane than the point C1, reference being had to any convenient datum plane, such as the track rail surface that is indicated (not to scale), by the line 18. Thus, the distance between the road-bed and the bottom of the motor frame may readily be varied to meet requirements. It will be appreciated that, by suitably varying the amount and angle of the offset in question, the point C2 may be shifted to any desired location, thereby securing whatever "gear-center-distance" and "road clearance" is needed.

It should be noted that, since the offset portions 3 and 4 may readily be made of equal respective lengths and inclinations, regardless of the amount of offset thereof from the adjacent frame portions, a single form of axle-bracket 5 may be associated with all of the motor frames that are employed to produce a line of motors having various "gear-center-distances", thereby tending toward desirable standardization of parts, with all of its well-known advantages.

On the other hand the same single form of axle-bracket may be employed with various angles of offset or tilting of the frame portions 3 and 4, by the use of suitable shims or filling-pieces 19, as illustrated, although,

of course, the lips 12 and 13 of the axle-bracket may be bent over at different angles to properly correspond to the particular angular positions of the offset portions 3 and 4, if desired.

I do not wish to be restricted to the specific structural details or arrangement of parts herein set forth, as various modifications thereof may be effected without departing from the spirit and scope of my invention. I desire, therefore, that only such limitations shall be imposed as are indicated in the appended claims.

I claim as my invention:

- 15 1. A dynamo-electric machine frame having a gap in one side, the edges thereof being offset a predetermined amount from the adjacent frame portions, and an axle-bracket member secured to said offset edges.
- 20 2. A dynamo-electric machine frame having a gap in one side, the edges thereof being offset a selected amount from the adjacent frame portions and adapted to receive an axle-bracket, the selected dimensions of
- 25 the offset edges determining the distance between the "center" of the motor frame and the axle-bracket position.
- 30 3. A dynamo-electric machine frame having a gap in one side, the edges thereof being offset a selected amount from the adjacent frame portions and adapted to receive an axle-bracket, said selected amount determining the "gear-center-distance" of the machine and also permitting the use of a

single type of axle-bracket with all frame members having such offset edges.

4. A dynamo-electric machine frame member having a gap in one side, the edges thereof being offset a selected amount and angle from the adjacent main portions of the frame and adapted to receive an axle-bracket, the selected angle of the offset edges determining the distance between a datum plane and the axle-bracket position.

5. A dynamo-electric machine frame member having a gap in one side, the edges thereof being offset a selected amount and angle from the adjacent main portions of the frame and adapted to receive an axle-bracket, said selected amount and angle respectively determining the "gear-center-distance" and the "road clearance" of the main frame member.

6. A railway-motor frame comprising a yoke member having a gap in one side thereof, the end portions of said yoke adjacent said gap being offset from the adjacent main portions of the yoke.

7. In a dynamo-electric machine, a stator member, comprising a magnetizable portion having a gap in one side, the edges thereof being offset a predetermined amount and angle from the adjacent main parts of said magnetizable portion.

In testimony whereof, I have hereunto subscribed my name this 18th day of Oct., 1916.

CHARLES W. STARKER.
